(57) CLAIM

The ornamental design for a display screen with icon, as shown and described.

DESCRIPTION

FIG. 1 is a front view of a display screen with icon showing our new design; and,

FIG. 2 is a front view of a display screen with icon showing our new design according to a second embodiment.

The broken line showing of a display screen with icon is included for the purpose of illustrating portions of the article that forms no part of the claimed design.

1 Claim, 2 Drawing SheetsFIG. 1
